UNITED STATES PATENT OFFICE

155,364

DESIGN FOR A DOUBLE-SPOON FISHING BAIT

Lewis Grant Rice, Montague, Mich.

Application November 2, 1948, Serial No. 149,439

Term of patent 7 years

(Cl. D31—4)

To all whom it may concern:

Be it known that I, Lewis Grant Rice, a citizen of the United States, residing at Montague, in the county of Muskegon and State of Michigan, have invented a new, original, and ornamental Design for a Double-Spoon Fishing Bait, of which the following is a specification, reference being had therein to the accompanying drawings, forming part thereof, in which

Figure 1 is a view in side elevation of a double-spoon fishing bait, showing my new design.

Figure 2 is an elevated edge view.

Figure 3 is a top plan view.

I claim:

The ornamental design, for a double-spoon fishing bait, as shown.

LEWIS GRANT RICE.
